UNITED STATES PATENT OFFICE.

JOSEPH T. MILLS, OF EAST ST. LOUIS, ILLINOIS.

OIL-STOVE BURNER.

1,172,546.

Specification of Letters Patent. Patented Feb. 22, 1916.

Application filed September 17, 1915. Serial No. 51,201.

To all whom it may concern:

Be it known that I, JOSEPH T. MILLS, a citizen of the United States, and resident of East St. Louis, Illinois, have invented 5 certain new and useful Improvements in Oil-Stove Burners, of which the following is a specification, containing a full, clear, and exact description, reference being had to the accompanying drawings, forming a 10 part hereof.

My invention relates to an improvement in "oil-stove burners" of that class which employ a wick for feeding the oil, and it consists in the novel construction and arrangement of parts hereinafter described 15 and definitely pointed out in the appended claims.

The object of my invention is to provide a means for holding the lower flange of the 20 flame-spreader of a round-wick burner up off of the end of the wick, to prevent "smoking", and to facilitate lighting of the wick, in that class of wick-burners illustrated by the "Perfection" heating and cook stoves, 25 heretofore patented by the assignor of the Standard Oil Company, an Indiana corporation.

In the drawings, Figure 1 is an elevation of a burner, partly in section, having my invention applied thereto, Fig. 2 is a sectional plan view of same, the section being taken on line 2—2 of Fig. 1, and Fig. 3 is an inverted plan of the lower end of the air-tube.

The numeral 1 indicates the usual reservoir, in which the "kerosene" or other oil 35 is placed, to be absorbed by the wick 2, which latter is located within the usual wick tube 3.

Mounted as usual within the said wick holder (or wick tube) 3 is the common three-armed spider 4, beneath the three arms of which the hooks 5 of the air-tube 6 engage, so that the said tube and the entire flame 40 spreader carrying both the upper and lower spreader-flanges will be detachably held within said wick-tube 3, during operation of the burner.

Heretofore, in that class of oil-stoves known on the market as the "New Perfection", much trouble and inconvenience has been occasioned by the fact that the weight 50 of said air-tube 6 and all of the spreader parts above it, caused the lower flame-spreader flange 7 to rest too near the upper end of said wick 2, and in some cases to rest directly upon said wick; thereby interfer-

ing with the combustion, and producing much disagreeable smoke, soot and odor, besides wasting the fuel in such useless production of smoke and soot. The soot was deposited upon the said lower spreader-flange 60 7 to such an extent that it interfered with the flame, and had to be removed by wiping or scraping. I avoid all such disagreeable action by inserting within said spreader 65 air-tube, or by attaching to some part of the spreader, an improved device for holding said lower spreader-flange up a distance from the upper end of said wick. In the present instance, I have shown a coil spring 70 8 for such purpose. The upper end of said spring 8 rests beneath the upper spreader-flange 9, in the present case, while its lower end rests upon the said arms of the said spider 4.

The operation is as follows: The said spring 8 being compressed by the act of inserting the spreader air-tube 6, within said wick-tube presses upward against the said upper spreader-flange 9, and lifts and holds 80 up the entire spreader until the said hooks 5 are held in contact with the under sides of the spider-arms, and until the lower spreader-flange 7 is supported at a distance above the end of said wick 2, and is held 85 thereat during the entire operation of the burner, thereby permitting ample space between said end of the wick and said lower flange to produce perfect combustion, and prevent smoke, soot and disagreeable odors. 90 The increased space between said lower flange 7 and the wick, also provides more room for the insertion of the match, in lighting the burner. The flame-spreader and its air-tube 6 are secured in position and detached in the usual manner, by partially rotating the same, to cause the said hooks 5 95 to engage or disengage the arms of the said spider 4.

What I claim is:

1. In a wick-fed burner for oil-stoves, the combination of a wick-tube, a wick, a flame-spreader provided with upper and lower spreading-flanges, an air-tube at the lower end of said spreader, a series of laterally-extending hooks at the lower end of said air-tube, a part fixed within said wick-tube at about the plane of said hooks and adapted to be engaged thereby, and a suitable spring located within said flame-spreader 105 and extending downwardly to a support fixed within said wick-tube, and having its 110

lower end resting thereon and its upper end in engagement with some suitable portion of the said flame-spreader, whereby the said spring will normally support the weight of the said flame-spreader, and will retain the said lower spreading flange a suitable distance above the plane of the wick, to prevent smoking.

2. In an oil-stove burner having the usual
10 wick-tube, a flame-spreader provided with upper and lower flame-spreading flanges, an air-tube having at its lower end laterally-projecting hooks, a spider having arms and fixed within said wick-tube, and a coil-spring located within said air-tube, with its lower end resting upon said spider and its upper end extending upward and engaging

the inner surface of the said upper spreading-flange, whereby the entire flame-spreader will be held yieldingly in position with said 20 lower spreading-flange elevated a distance above the upper end of said wick-tube and the wick carried thereby; the said hooks normally engaging the undersides of said spider-arms, to prevent said spring from 25 lifting the parts too high.

In testimony whereof, I have signed my name to this specification, in presence of two subscribing witnesses.

JOSEPH T. MILLS.

Witnesses:

A. G. HAGETER,
JOHN C. HIGDON.
